DESIGN FOR AN ASH TRAY

James N. Wright, Jr., Pasadena, Calif.

Application June 17, 1940, Serial No. 93,053

Term of patent 3½ years

To all whom it may concern:

Be it known that I, James N. Wright, Jr., a citizen of the United States of America, residing at Pasadena, in the county of Los Angeles and State of California, have invented a new, original, and ornamental Design for an Ash Tray, of which the following is a specification, reference being had to the accompanying drawing, forming part thereof.

Figure 1 is a top or plan view of an ash tray showing my new design; Fig. 2 is a sectional view taken from the line 2—2 of Fig. 1; and Fig. 3 is a sectional view taken from the line 3—3 of Fig. 1.

I claim:

The ornamental design for an ash tray, substantially as shown.

JAMES N. WRIGHT, JR.
